TROUSERS PRESSING MACHINE

Arthur B. Jones, Detroit, Mich.

Application August 31, 1949, Serial No. 113,293

3 Claims. (Cl. 223—57)

1

This invention relates to pressing machine and, in particular, to trousers pressing machines.

Hitherto, pressing machines have been constructed with the pressing members horizontal, with the result that such machines occupy a large amount of floor space, can only be used to press one leg of a pair of trousers at a time, and require careful arrangement of the trousers to prevent wrinkles and undesired folds. Furthermore, such machines have been wasteful of heat due to the natural tendency of heat to rise, and have also been wasteful of labor due to the necessity of pressing each leg separately and of carefully arranging the trousers before closing the machine to start pressing. In the use of prior pressing machines where the pressing members have been arranged vertically, the trousers have been held in an inverted position with the cuffs held above the pressing members or near the upper ends thereof and the waistband at the bottom thereof. Since there are two folds required on a large pair of trousers and at least one fold on a small pair of trousers, the operator of such prior machines always has had to stoop down to make the folds at their proper positions. Such alternate stooping and rising required for pressing every pair of trousers is fatiguing to the operator and usually requires giving additional pay to the operator because of such fatigue.

One object of this invention is to provide a trousers pressing machine in which the trousers are held upright with the waistband portion thereof supported above the pressing members and with the legs hanging downward so that both sides of both legs of the trousers are pressed simultaneously, thereby eliminating a series of operations previously necessary where the trousers legs have been pressed in separate operations and also eliminating the alternate stooping and rising in making the folds.

Another object is to provide a trousers pressing machine of the foregoing character in which the trousers are held vertically while the pressing operations are carried out, thereby reducing to a minimum the floor space occupied by the machine, economizing on heat because of the natural tendency of heat to rise, and eliminating wrinkles occurring in horizontal types of machines.

Another object is to provide a trousers pressing machine of the foregoing character in which the trousers are suspended from the waistband above the machine, with the legs of the trousers extending downward into the machine.

In the drawings:

2

Figure 1 is a side elevation of a trousers pressing machine according to one form of the invention, with one of the outer pressing members broken away to disclose the steam connections to the inner member;

Figure 2 is a top plan view of the trousers pressing machine shown in Figure 1;

Figure 3 is a front elevation, partly in vertical section, of the trousers pressing machine shown in Figures 1 and 2;

Figure 4 is a horizontal section taken along the line 4—4 in Figure 1;

Figure 5 is a diagrammatic perspective view of a pair of trousers for a person of ordinary build, showing the manner of folding it prior to inserting it in the machine; and

Figure 6 is a similar view showing the manner of folding a pair of trousers for a stout person.

Referring to the drawings in detail, Figures 1 to 3 inclusive show a pressing machine, generally designated 10, according to a preferred form of the invention as mounted upon a base 11 which is secured to the floor of the room in which it is to be used. Bolted or otherwise secured to the rearward portion of the base 11 is a free-standing vertical post or standard 12 which is hollow and terminates at its upper end in a vertical bore 13 of square or rectangular cross-section and serves to receive an elongated bar 14 of similar cross-section adjustably held in position by a thumb screw 15 threaded into a threaded transverse hole 17 in the upper end of the post 12. Extending substantially horizontally forward from the bar 14 is a rod 18 carrying a pair of clamps 19 for holding the waist band of the trousers T. The clamps 19 are pivoted on the rod 18 and include a pair of opposed members 20 having jaws 21 on the lower side of the rod 18 and handles 22 on the upper side thereof, a spring 23 forcing the handles 22 apart so as to close the jaws 21 upon the trousers T.

Bolted or otherwise secured to the forward portion of the base 11 is a substantially vertical pedestal 24 upon which is mounted a free-standing elongated hollow inner or central pressing member, generally designated 25. The pressing member 25 being free-standing, is thus supported wholly by the base 11 without lateral braces, and consists of a vertically elongated hollow body 26 of metal or other suitable heat-conducting material, of approximately rectangular cross-section and having a steam chamber 27 (Figure 4) with multiple steam vents 28 in the side walls thereof. Secured to the opposite sides of the pressing member 25 are pads 29 of porous mate-

rial, such as textile material, surrounded by an envelope or retaining sleeve 30 likewise preferably of porous material, such as textile material. By reason of the free-standing construction of the inner pressing member 25, it will be evident from Figures 1 and 3 that the envelope 30 can be and is drawn downwardly thereover, like pulling a sock on one's foot, since there are no braces, supporting arms or other projections to interfere. The body 26 of the inner pressing member 29 is preferably tapered near its upper end 31 and its length is preferably sufficient to accommodate the legs of the longest pair of trousers ordinarily encountered. The chamber 27 near the upper end 31 is closed by the top end portion 32 (Figure 3) and over this is mounted an end pad 33. The envelope 30 is closed at its upper end like a stocking or bag and fits snugly down over the pads 29 and hollow body 26.

Steam is admitted to the central or inner pressing member 25 through ports 34 and 35 in vertically spaced inlet and exhaust bosses 36 and 37 (Figures 1 and 3) in the rearward edge wall of the body 26. Rising from the base 11 and bolted or otherwise secured thereto is a bracket 38 upon which are mounted steam intake and exhaust valves 39 and 40 located one above the other and having intake and exhaust pipes 41 and 42 connected thereto. The valves 39 and 40 are operated by valve levers or arms 43 and 44 interconnected by a link 45, one of the valves, such as the valve 40, having an additional arm or lever 46 connected to the rotary valve member thereof (not shown) and having an operating rod 47 pivoted thereto at its rearward end, and extending forwardly to a pivotal connection with a bell crank lever 48 pivotally mounted as at 49 on a vertical bracket 50 which rises from and is bolted or otherwise secured to the base 11 at the forward end thereof. The upper arm of the bell crank lever 48 terminates in a pedal 51. A pin 52 connected to the link 45 carries the upper end of a tension spring 53, the lower end of which is connected to an arm 54 which is bolted or otherwise secured to the rearward end of the base 11. The spring 53 thus constantly urges the link 45 and the valve levers 43 and 44 downward to normally close the steam inlet valve 39 and normally open the steam outlet or exhaust valve 40. When the operator steps on the pedal 51, however, the valve levers 43 and 44 are swung upwardly to open the steam inlet valve 39 and close the exhaust valve 40. Steam inlet and exhaust pipes 55 and 56 run from the steam inlet and exhaust ports 34 and 35 to the valves 39 and 40 respectively. In order to carry away condensate from the inner or central pressing member 25, the hollow body 26 at its lower end is provided with a drain port 57 in a boss 58, from which a drain pipe 59 leads to a suitable receiver or condensate pump.

Extending outwardly from the upper and lower portions of the standard 12 are upper and lower ears 60 and 61 extending outward laterally in opposite directions (Figures 2 and 4). Pivotally mounted in the ears 60 and 61 are upper and lower pivot pins 62 and 63 connected to vertical members 64 forming the uprights of a pair of U-shaped brackets 65 mounted on opposite sides of the standard 12 and having upper and lower arm portions 66 and 67 (Figure 1) secured as at 68 and 69 to swinging outer pressing members, generally designated 70, arranged on opposite sides of the inner or central pressing member 25.

The outer pressing members 70 consist of elongated hollow bodies 71 likewise preferably of elongated rectangular cross-section and having steam vents 72 in their inner walls (Figure 4). The outer pressing members 70 are likewise provided with pads 73 preferably of porous textile material and this in turn is similarly covered by an envelope or cover 74 resembling the envelope 30 for the central pressing member 25. In actual practice, insulation is preferably applied to the outer walls of the outer members 70, but this is omitted to simplify the showing. The outer walls of the bodies 71 are provided with upper and lower bosses 75 and 76 containing steam intake and exhaust ports 77 and 78 (Figure 3) to which are connected steam intake and exhaust pipes 79 and 80 having flexible portions 81 and 82 respectively permitting the pressing members 70 to be swung outward and inward without interrupting the steam connections. The lower ends of the bodies 71 are provided with partitions 83 with drain holes 84 opening into sumps 85, and drain ports 86 in bosses 87 are provided at the lower ends of the sumps 85 and have drain pipes 88 and flexible portions 89 connected thereto for carrying away the condensate.

Extending rearwardly from the standard 12 (Figure 1) is an arm 90 to the rearward end of which a vertical bracket 91 is bolted or otherwise suitably secured. Mounted on the upper and lower ends of the bracket 91 are steam intake and exhaust valves 92 and 93 respectively connected to steam intake and exhaust pipes 94 and 95. The valves 92 and 93 are operated by valve levers 96 and 97 pivotally interconnected by a link 98 which is constantly urged in an upward direction by a coil spring 99 attached at its lower end to a pin 100 on the link 98 and at its upper end to a pin 101 mounted on the bracket 91. In a manner similar to the spring 53 of the valves 39 and 40, the spring 99 constantly urges the valve levers 96 and 97 into a normally closed position for the steam intake valve 92 and a normally open position for the steam exhaust or outlet valve 93. An additional lever or arm 102 is connected to the valve lever 97 and in turn is pivotally connected to an operating rod 103, the forward end of which is pivotally connected to one arm of a bell crank lever 104 which is pivoted at 105 to the upper end of a bracket 106, the lower end of which is bolted or otherwise suitably secured to the base 11. The other arm of the bell crank lever 104 terminates at its outer end in a pedal 107.

In order to open and close the outer pressing members 70 by swinging them outward and inward around the pivot pins 62 and 63, a toggle linkage is provided wherein the lower arms 67 of the U-shaped brackets 65 are extended as at 108 (Figure 4) beyond their pivots 63 and carry pivot pins 109 to which are pivotally connected the forward ends of links 110, the rearward ends of which are connected as at 111 to the cross bar of a T-member 112, the other bar of which carries the pivot pin 113. Connected to the pivot pin 113 is a link 114, the opposite end of which is pivoted to a pivot pin 115 carried by the upper end of a crank arm 116 which is mounted upon a shaft 117 journaled in the arm 99 of the standard 12 (Figure 1). Secured to the opposite end of the shaft 117, as by a pin or key, is a bent lever 118 extending forwardly and having a pedal 119 at the forward end of the base 11 adjacent the pedals 51 and 107. In order to normally hold the outer pressing members 70

in their open position shown in Figure 4, a tension spring 120 is connected at its lower end to a pin 121 on the bent lever 118 and at its upper end to a pin 122 extending outward from one of the ears 61.

Operation

In the operation of the invention, let it be assumed that the inlet pipes 41 and 94 have been connected to a source of steam under pressure, and that the steam exhaust pipes 42 and 95 have been similarly connected to a steam outlet or receiver, also that suitable connections have been made to the condensate drain lines 53 and 89 to carry away the condensate. Let it also be assumed that the machine is in its open position (Figure 4) with the spring 120 holding it in this position. To press a pair of trousers T, the operator first grasps the waistband W and forms a fold F in the forward side thereof (Figure 5) if the trousers are for a person of ordinary girth. For a stout person, the operator folds the trousers T with an additional fold G at the rearward end of the waistband W (Figure 6). The folds F and G are not pressed into the trousers by the machine since they are outside the pressing members 25 and 70. With the trousers T thus folded, the operator mounts the waistband W thereof in the clamps 19 with one clamp at the forward end and the other at the rearward end (Figure 1). While he is moving the waistband into the clamping position, he preferably at the same time inserts the trousers legs L on opposite sides of the central or inner pressing member 25 in the spaces between it and the now open outer pressing members 70.

The operator then steps on the pedal 119 and thereby swings the outer pressings members 70 into engagement with the trousers legs and forces them against the central or inner pressing member 25. The bent lever 118 is preferably provided with a conventional locking pawl (not shown) so that the operator may step off the pedal 119 while leaving the machine in its closed position.

The operator then steps on the pedals 51 and 107 to the extent necessary to apply steam to the inner and outer pressing members 25 and 70. This steam escapes through the vents 28 and 72 from the interior of the hollow bodies 26 and 71 and penetrates the pores of the pads 29 and 73 and covers or sleeves 30 and 74, entering the interstices between the threads of the trouser legs, thereby moistening the material. The combination of heat and pressure in this manner simultaneously presses both sides and the forward and rearward creases of both trouser legs L in a single operation. When pressing has been completed, the operator releases the pedals 51, 107 and 119 permitting the steam to exhaust from the pressing members 25 and 70 and at the same time swinging the latter open into the position shown in Figure 4.

What I claim is:

1. A trousers pressing machine for simultaneously pressing both legs of a pair of trousers in their right-side-up position, said machine comprising a supporting structure, a vertically-elongated hollow inner pressing member mounted vertically on said structure, a pair of vertically-elongated hollow outer pressing members movably vertically on said structure on opposite sides of said inner pressing member, means connected to said outer pressing members for moving said outer pressing members into and out of close proximity to said inner pressing member, means

for supplying heat to said pressing members, and a trousers support connected to said supporting structure and overhanging said inner pressing member, said trousers support having thereon trousers waistband grippers releasably engageable with the waistband portions of the vertically-folded and vertically-hanging trousers near the forward and rearward edges of the trousers on opposite sides thereof whereby to press the legs of said trousers in the right-side-up position of said trousers.

2. A trousers pressing machine for simultaneously pressing both legs of a pair of trousers in their right-side-up position, said machine comprising a supporting structure, a vertically-elongated hollow inner pressing member mounted vertically on said structure, a pair of vertically-elongated hollow outer pressing members movably mounted vertically on said structure on opposite sides of said inner pressing member, means connected to said outer pressing members for moving said outer pressing members into and out of close proximity to said inner pressing member, means for supplying heat to said pressing member, and a trousers support connected to said supporting structure and overhanging said inner pressing member, said trousers support having thereon trousers waistband grippers releasably engageable with the waistband portions of the vertically-folded and vertically-hanging trousers near the forward and rearward edges of the trousers on opposite sides thereof, said trousers waistband grippers comprising horizontally-spaced waistband clamps depending from said trousers support above the forward and rearward portions of said inner pressing member whereby to press the legs of said trousers in the right-side-up position of said trousers.

3. A trousers pressing machine for simultaneously pressing both legs of a pair of trousers in their right-side-up position, said machine comprising a supporting structure, a vertically-elongated hollow inner pressing member mounted vertically on said structure, a pair of vertically-elongated hollow outer pressing members movably mounted vertically on said structure on opposite sides of said inner pressing member, means connected to said outer pressing members for moving said outer pressing members into and out of close proximity to said inner pressing member, means for supplying heat to said pressing members, and a trousers support connected to said supporting structure and overhanging said inner pressing member, said trouser support having thereon trousers waistband grippers releasably engageable with the waistband portions of the vertically-folded and vertically-hanging trousers near the forward and rearward edges of the trousers on opposite sides thereof, said pressing members being wider at their upper ends than at their lower ends and having their forward and rearward edges tapering from their upper ends downwardly toward their narrower lower ends whereby to press the legs of said trousers in the right-side-up position of said trousers.

ARTHUR B. JONES.
